UNITED STATES PATENT OFFICE.

OTTO M. BRAUER, OF MARSHALLTOWN, IOWA.

CARBID-FEEDER.

No. 821,332.

Specification of Letters Patent.

Patented May 22, 1906.

Application filed November 25, 1905. Serial No. 289,122.

To all whom it may concern:

Be it known that I, OTTO M. BRAUER, a citizen of the United States, residing at Marshalltown, in the county of Marshall and State of Iowa, have invented certain new and useful Improvements in Carbid-Feeders, of which the following is a specification.

This invention relates to improvements in acetylene-gas generators, and particularly to an improved construction of feeding mechanism for the carbid.

The object of my invention is to provide an improved carbid-feeding device which will be certain in its operation and not liable to get out of order and which is provided with an improved construction of feeding devices and agitating devices so arranged to coöperate in their operation that the latter will always insure that the carbid is fed properly to the former, the said feeding devices being also so arranged that they may readily pass over lumps of carbid in their travel and will accommodate themselves to the inequalities caused thereby without injury.

For a full description of the invention and the merits thereof and also to acquire a knowledge of the details of construction of the means for effecting the result reference is to be had to the following description and accompanying drawings, in which—

Figure 1 is a vertical sectional view of my improved carbid-feeding device. Fig. 2 is a top plan view thereof. Fig. 3 is a detail perspective view illustrating the hood of the holder. Fig. 4 is a detail perspective view illustrating the spider carrying the scraper devices and agitating devices. Fig. 5 is a detail view illustrating the pivotal connection between the scraping feed devices and the vertical shafts that carry the same.

Corresponding and like parts are referred to in the following description and indicated in all the views of the drawings by the same reference characters.

Referring to the drawings, 1 designates the shell of the carbid-holder, which may be of any desired construction so far as its general structure is concerned, and 2 designates the feed-chute designed to convey the carbid from the holder to the generating-tank. (Not shown.) In the present instance the said chute directly supports the carbid-holder, and the latter is provided in its bottom 3 with a central opening 4 for the passage of the carbid and with a central conical hood 5, the lower edge 6 of which extends somewhat

beyond the margin of the opening 4 and is spaced vertically from the bottom 3 of the shell 1.

7 designates a vertical shaft, which has one of its bearings in the upper end of the shell 1 and which projects downwardly therefrom through the hood 5 and preferably to and through the opening 4. At a predetermined point on the shaft 7 there is mounted a cross-bar 8, provided with a sleeve 8^a, secured to the shaft by a set-screw, as shown, and each arm of the cross-bar 8 is provided with a downwardly-extending finger 9. A spider 10, provided with any desired number of radial horizontally-extending arms 11, is formed with a vertical tubular stem 12, inserted over and spaced from the lower end of the shaft 7, and the said spider is provided at the upper end of said stem 12 with an outwardly-projecting yoke 13, the two members of which are provided with apertures 14, receiving the fingers 9, respectively. The said apertures 14 are preferably somewhat larger than the said fingers 9. Each of the radial arms 11 of the spider 10 carries a vertical shaft 15, extending both above and below the arm. To the lower end of each shaft 15 a scraping feed device 16 is pivotally mounted intermediate its ends, so as to rock or oscillate in a vertical plane. To the upper end of each shaft 15 there is secured an agitator 17, which is resilient or is resiliently mounted, so that its free end will bear outwardly upon the body of carbid contained within the holder. The conical hood 5 may be secured within the shell 1 in any desired manner, in the present instance brackets 19 being utilized for this purpose.

In the practical operation of my improved carbid-feeding mechanism it is to be assumed that the shaft 7 is connected to any suitable form of motor or other actuating mechanism. In the present instance I have shown a weight-motor (designated 20) for this purpose; but it is to be understood that I am not limited to any particular mechanism for turning the said shaft. As the shaft turns the scraping devices 16 will be carried around the body of the carbid contained within the shell 1, and owing to their tangential arrangement with respect to their line of travel they will scrape the carbid into the central opening 4, through which it will drop into the generating-tank. As the agitating devices or arms 17, which are preferably made of round or flat spring-wire, are also carried around the body

of carbid above the scraping device 16, they will effect an agitation of the carbid and cause it to roll down in front of the scrapers, thereby preventing the carbid from becoming caught or lodged in the lower contracted end of the holder.

It will be noticed that the opening in the stem 12 of the spider 10 is larger than the shaft 7, as are also the openings 14 in the yoke 13 with respect to the fingers 9, which they accommodate. By this arrangement as the shaft 7 is turned the fingers 9 will bring up against the outwardly-extending portion of the yoke 13 to cause a horizontal revolution of the spider 10 with its two sets of blades, and at the same time the arrangement provides that the spider as a whole may slightly rock and yield on the shaft 7, and thereby accommodate itself to any lumps of carbid that might otherwise tend to wedge or work under the scrapers 16 and injure the mechanism. Owing to the fact that the devices 16 are pivoted intermediate their ends, so as to have a slight oscillatory movement, they may yield vertically at either end on the opposite end as a fulcrum and will independently swing up over any piece of carbid that might be in their way and maintain their circular path on the bottom 3 of the holder without undue strain of the parts. In other words, by my invention I am enabled to provide means for permitting the entire set of scraping devices to yield vertically in a body and also provide means for allowing each of said devices to yield vertically independently of the others by the oscillatory movement above described.

It is to be understood that the spider is supported from downward longitudinal displacement solely by the engagement of the scraping devices 16 on the bottom 3 of the shell 1 and that, consequently, the spider 10 may yield bodily in an upward direction, as well as rock from side to side to compensate for all the inequalities of the surface over which it travels, such inequalities being, for instance, produced by the wedging of the carbid underneath one or more of the scraping devices.

It is to be understood that my invention is not limited to the details of construction or precise arrangement of parts before described, and illustrated in the accompanying drawings.

Having thus described the invention, what is claimed as new is—

1. A carbid-feed device comprising a holder provided with a discharge-opening, a set of scraping devices in said holder, means for revolving said scraping devices, and means whereby all of said devices may yield vertically as a body and also yield vertically one independently of the others.

2. A carbid-feed device, comprising a holder provided with a discharge-opening, a set of scraping devices in said holder, means for revolving said scraping devices, and means whereby each scraping device may yield vertically independently of the others.

of scraping devices carried by said shaft, means whereby said devices may yield vertically as a body on said shaft, and means whereby each scraping device may yield vertically independently of the others.

3. A carbid-feed device comprising a holder provided with a discharge-opening, a revoluble shaft mounted in said holder, a spider yieldingly mounted on said shaft to move in a vertical direction, and a set of scraping devices each of which is pivotally mounted on said spider independently of the others and arranged to move vertically each independently of the others.

4. A carbid-feed device comprising a holder provided with a discharge-opening, a revoluble shaft mounted in said holder, a set of scraping devices in said holder, a connection between said shaft and said scraping devices whereby the rotation of the shaft will effect the revolution of the scraping devices, means whereby the scraping devices may yield as a whole vertically, and means whereby one scraping device may oscillate vertically independently of the others.

5. A carbid-feed device, comprising a holder provided with a discharge-opening, a revoluble shaft mounted in said holder, a set of scraping devices in said holder and designed to rest on the bottom thereof, means whereby the rotation of said shaft will effect a revolution of said scraping devices and means whereby each scraping device may rock vertically independently of the others.

6. A carbid-feed device, comprising a holder provided with a discharge-opening, a revoluble shaft mounted in said holder, a spider in said holder, scraping devices carried by said spider, means whereby said spider may move freely in a vertical direction on the shaft, and means whereby a rotation of said shaft will effect a rotation of the spider.

7. A carbid-feed device, comprising a holder provided with a bottom discharge-opening, a set of scraping devices mounted in said holder and resting on the bottom thereof, means for revolving the set of scraping devices around the bottom of the holder, means whereby the set of scraping devices may yield vertically as a body with respect to the revolving means, and means whereby each scraping device may yield vertically independently of the others.

8. A carbid-feed device, comprising a holder provided with a bottom discharge-opening, a set of scraping devices in said holder and designed to rest on the bottom thereof, and means for revolving said scraping devices around the bottom of the holder, said means including a vertically-yieldable support, and the scraping devices being pivotally mounted on said support, as and for the purpose set forth.

9. A carbid-feed device comprising a

holder provided with a discharge-opening, a hood within said holder with its lower edge spaced from the bottom thereof and surrounding said discharge-opening, a spider mounted within the hood and provided at the outer ends of its arms with shafts, scraping devices carried on the lower ends of said shafts, agitators carried by the upper ends of said shafts, and means for rotating said spider.

10. A carbid-feed device comprising a holder provided with a discharge-opening, a spider mounted in said holder, a vertical shaft 15 carried by said spider, a scraping device pivotally mounted on the lower end of said shaft, a spring-agitator secured to the upper end of said shaft, and means for rotating said spider.

11. A carbid-feed device comprising a holder provided with a discharge-opening, a revolute shaft mounted in said holder, depending fingers carried by said shaft, a spider provided with a yoke having apertures receiving said fingers, whereby the rotation of the shaft will impart movement to said spider, and a scraping device carried by said spider.

12. A carbid-feed device comprising a holder provided with a discharge-opening, a revolute shaft within said holder a cross-bar secured to said shaft and provided with depending fingers, a spider provided with a stem surrounding and spaced from said shaft and also provided with an apertured yoke receiving said fingers, and scraping devices carried by said spider.

13. A carbid-feed device comprising a holder provided with a discharge-opening, a

revolute shaft mounted in said holder, a cross-bar secured to said shaft and provided with two downwardly-extending fingers, 40 a spider surrounding and spaced from said shaft and provided at its upper end with an apertured yoke receiving said fingers, the said apertures in the yoke being of larger diameter than the fingers, and scraping devices 45 carried by said spider.

14. A carbid-feed device comprising a holder provided with a bottom discharge-opening, a revolute shaft mounted in said holder, a cross-bar provided with a sleeve by 50 which it is secured to said shaft, in connection with a set-screw, said cross-bar being provided with two downwardly-extending fingers, a spider provided with a plurality of radial arms, vertical shafts carried at the 55 outer ends of said arms, agitating devices secured to the upper ends of said shafts, scrapers secured to the lower end of said shafts and pivotally mounted thereon intermediate of their ends, said scrapers resting on the bottom 60 of the holder, the said spider being further provided with a tubular stem surrounding and spaced from the lower end of the said shaft and formed at its upper end with an outwardly-projecting yoke, the arms of said 65 yoke being formed with apertures loosely receiving the said downwardly-extending fingers, and means for revolving said shaft.

In testimony whereof I affix my signature in presence of two witnesses.
